UNITED STATES PATENT OFFICE.

ALFRED MORFITT AND CHARLES BUTTERFIELD, OF NOTTINGHAM, ENGLAND.

PLATEN PRINTING-MACHINE.

SPECIFICATION forming part of Letters Patent No. 439,281, dated October 28, 1890.

Application file September 4, 1888. Serial No. 284,558. (No model.) Patented in England September 23, 1887, No. 12,891; in France August 7, 1888, No. 192,279, and in Germany December 6, 1889, No. 49,908.

To all whom it may concern:

Be it known that we, ALFRED MORFITT, a subject of the Queen of Great Britain, and a resident of Hockley Mill, Nottingham, in the county of Nottingham, England, and CHARLES BUTTERFIELD, also a subject of the Queen of Great Britain, and a resident of 62 Woodhouse Street, Nottingham, in the county of Nottingham, England, have invented new and useful improvements in platen printing-machines for taking off the paper cards, or other material being printed from the platen and delivering the same upon the table in front of the operator and with its printed side uppermost; and we do declare the following to be a full, clear, and exact description of the invention, such as will enable others skilled in the art to which it appertains to make and use the same, reference being had to the drawings and the letters of reference marked thereon, which drawings form a part of this specification.

This invention was patented to us in Great Britain, No. 12,891, dated September 23, 1887; 25 in France, No. 192,279, dated August 7, 1888, and in Germany, No. 49,908, dated December 6, 1889.

This our invention relates to certain new and useful improvements in platen printing-machines, and which invention has for its object to facilitate the taking off of the paper, cards, or other material being printed from the platen and to deliver said sheets with their printed sides uppermost upon the table 35 in front of the operator.

We now proceed to describe our said invention, reference being had to the accompanying drawings and the letters of reference marked thereon, similar letters indicating 40 like parts throughout.

Figure 1 represents a side elevation of a platen printing-machine, showing the manner in which our invention is applied thereto. Fig. 2 is a detached elevation of our invention separate from the other well-known parts of the machine, and Fig. 3 is a plan of same. Figs. 4 and 5 are detail views of portions of the platen, showing the tumbler-cam and connections carrying the oscillating le-

vers, only one of which is shown. Fig. 6 is 50 a detail view of the lifter-bar and the mechanism appertaining thereto. Figs. 7, 8, and 9 are detail views of the lifter brackets and fingers. Fig. 10 is a side elevation of a platen printing-machine, showing a modified form of 55 our invention applied thereto. Fig. 11 is a detached elevation of our invention in its modified form, and Fig. 12 is a part front elevation of same. Fig. 13 is a part side elevation of a platen printing-machine, showing a 60 modification in our invention, as shown in Fig. 10. Figs. 14 and 15 are detail plan views of the lifter-bar and mechanism appertaining thereto. Fig. 16 is an end elevation of Fig. 15.

In the drawings we have shown only such 65 parts of a platen printing-machine as will enable us to describe and illustrate our invention and in what manner the same is operated.

A represents one of the arms, attached to 70 the platen B by means of the stud b and clip b', as shown in enlarged detail in Figs. 4 and 5. Firmly attached to an axle protruding at the extremity of the arm A is a lever C, which carries at its upper end the lifter-bar D. 75 Hinged or pivoted to the lifter-bar D at d is the rod d' and lever d², the lever d² carrying an axle and truck d³, said lever d² being acted upon by a spiral spring d⁴, which keeps it in its normal position. Suitably attached to the 80 lifter-bar D and the hinged or pivoted rod d' are the fingers d⁵ and brackets d⁶, to which are hinged or pivoted at d⁷ the lifters d⁸.

Fixed to the platen B is a frame E, which is adapted to be moved up or down a slot in 85 the platen, for adjustment, and in which frame E is pivoted a tumbler-cam e, which is formed with a projection e² to prevent its turning when the truck d³ passes over a projection e³. The truck d³ runs up from the angular position of projection e², which causes the fingers d⁵ to be opened, and said truck d³ having passed this projection the spring d⁴ presses the lever downward, and said fingers are thereby closed. Said truck d³ in its return 90 movement passes under the projection e², and the tumbler-cam is turned over on its axis, so that said truck may pass it without giving 95

motion to the lever. Said tumbler-cam then turns back into its normal position by reason of the weight of the projection e' .

The lower end of the lever C has a truck c , 5 mounted upon an axle, and which truck is kept in close contact with the plain wheel F by the spring c' , coiled around the axle a and having one extremity bearing against a stud or projection a' in the arm A and the other extremity bearing against the lever C, as shown at c^2 . Said lever C also carries a projection c^3 , which is pushed outward by the adjustable truck g , mounted in the connecting-link G.

15 Suitably attached to the platen-stop H is a rod h , having at one extremity an adjustable screw and nut h' for operating the friskets L. A spring h^2 , fixed to the frisket-bar i, releases the friskets when the stop H is knocked 20 out.

The table J is provided with stops or guides j for the purpose of guiding the printed sheets. A shield j' , in combination with a cam j^2 , is also attached to the table J or to the frame of 25 the machine. The cam j^2 serves to raise the lever d^2 when the lever C is in its backward position, thus opening the fingers and releasing the printed sheets at the proper time.

A modified form of our invention is necessary when it is to be applied to certain platen 30 printing-machines which have the axis of vibration of the platen below the center of the platen. Said modification may be described as follows, reference being had to Figs. 7 to 16 35 of the drawings.

K represents a lever mounted at one end upon a shaft k and having at its other end a truck K', which is adjustable in the slot K ^{2} . The shaft k has formed upon its circumference 40 a flat surface k' , which is adapted to receive the bridge k^2 , which by means of the set-screw k^3 serves to hold the lever L securely to the shaft k . Coiled around a boss situated at the lower end of the lever L is a 45 spring l , one end of which bears against a projection l' and the other end bears against a bracket l^2 , which carries the aforescribed mechanism. The spring l has a constant tendency to keep the lever in its outward or 50 backward position against the stop l^3 , and it also serves to keep the truck K' against the periphery of the cam M, or, as shown in an alternative form, Fig. 13, the truck K', mounted at the end of the lever L', against the adjustable cam g' , carried by the connecting-link G. Said cams M and g' impart an oscillating to-and-fro movement to the levers L' and L and levers K and L.

At the upper end of the lever L is suitably 60 hinged at n' the lifter-bar N', which is pressed upward against a stop l^4 on lever L by the spring M ^{2} , one end of which presses against a small projection on lever L at l^5 and the other end against the lifter-bar N'. Suitably 65 attached to the lifter-bar N' is the lever m' , Fig. 14, at one end of which is mounted the truck m^2 , which when brought into contact

with the cam B', carried by the platen B, causes the lifter-bar N' to be pressed downward. Journaled to centers or bearings m^3 70 upon the lifter-bar N' is a rod M ^{3} and lever m^4 , having a tail-piece at one end and at its other extremity a truck M ^{4} . The journaled rod M ^{3} carries the fingers d^5 , above referred to, and suitably attached to the lifter-bar are 75 the brackets d^6 , to which are hinged or pivoted at d^7 the lifters d^8 , having projections at their inner ends, which are acted upon by spring d^9 , Figs. 7, 8, and 9. The fingers d^5 on the hinged rod M ^{3} , in their normal position 80 lie between the lifter-hinges d^7 and press upon the lifters d^8 by the tension of the spring M ^{2} , one end of which bears against the lifter-bar N' and the other end against the lever m^4 .

Pivoted in a frame E upon the platen B is 85 the tumbler-cam e, as in the before-described construction.

The operation of our said invention is as follows: The movement of the oscillating lever L to remove a printed sheet is in the opposite direction to the platen, and is so timed that the truck m^2 shall pass under the cam B' when the platen has nearly completed its backward motion after the impression has been taken and as the lifter-bar N' descends 95 to take the sheet, said lifter-bar being movable in their centers. The fingers and lifters are adjusted to the varying angles of the platen B by the cam B', which presses the lifter-bar N' in the opposite direction to the 100 tension of the spring, and the lifters are thereby guided to the paper to be picked up. As the lifter-bar descends, the truck M ^{4} , carried upon the lever m^4 , passes over the projection e^2 of the tumbler-cam e, thus causing 105 the fingers d^5 to be opened, and the lifters d^8 , being freed, fall upon the platen B or blanket, to which they are kept in close contact by the spring d^9 . By a still further downward movement of the lifter-bar N' said lifters d^8 110 are carried under the printed sheet and lift it between themselves and the fingers d^5 . At this time the truck M ^{4} falls over the end of the projection e^2 of the tumbler-cam e, and the fingers d^5 , closing upon the lifters d^8 , push 115 the inner projections downward, thereby causing the points of the lifters to pick up the printed sheet from the platen. The fingers d^5 and the lifters d^8 now simultaneously close upon it, and the levers C L move backward to 120 take the sheet from the platen. The truck M ^{4} , going under the projection e^2 , turns the tumbler-cam over and passes on without giving motion to the lever m^4 . The tumbler-cam e then falls into its normal position. When 125 the tail-piece of the lever m^4 comes in contact with the shield l^6 , Figs. 10 and 13, or the cam j^2 , Figs. 1 and 2, the fingers d^5 and lifters d^8 are simultaneously opened, and the paper is released. The lifters d^8 turn upon their axes, 130 and the projections upon their inner ends move upward by the pressure of the spring d^9 , and the printed sheet is delivered and guided onto the table J at the same time as the levers

C and L are completing their outward movement. The stop l^3 prevents the levers C and L from being carried too far back by the springs c and l. Our taking-off mechanism is capable of being wholly thrown out of gear for convenience in making "ready," and is, moreover, adjustable so as to take the sheets from various positions of the platen in the direction of its depth, and which adjustment may be effected in one of the following ways: by moving the truck K' in the slot K² of the lever K, by moving the cam e in its slot, or by moving the cam g' in the socket at the end of the connecting-link G. By releasing the set-screw k³ in the bridge k² or by moving the projection in the clip the taking-off mechanism may be thrown out of use altogether, and the lifters remain stationary under the shield j' and l', and the machine may be used in the usual way without them.

Having now particularly described and ascertained the nature of our said invention, and in what manner the same is to be performed, we declare that what we claim is—

1. In a platen printing-machine, the combination of the arm C, the projection c³, carried by the arm C, said projection being adapted to engage with the truck g, the truck c, made to bear against the plain wheel F, and the axle a, all substantially as and for the purposes hereinbefore set forth.

2. In a platen printing-machine, the combination of the arm C, secured upon the axle a, the spring c', one end of which bears against the projection a' and the other end against the lever C, the lifter D, secured to the lever C, the rod d', lever d², attached to said lifter-bar D, the truck d³, mounted upon the lever d², the spring d⁴, acting upon said lever d², the brackets d⁵, attached to the lifter-bar D, the fingers d⁶, attached to the hinged rod d', and the lifters d⁸, hinged in said brackets, all substantially as and for the purposes hereinbefore set forth.

3. In a platen printing-machine, the combination of the platen B with the frame E, adjustable in a slot in said platen, and the tumbler-cam e, hinged in said frame E, all substantially as and for the purposes hereinbefore set forth.

4. In a platen printing-machine, the combination, with the platen-stop H, of the bar h, attached thereto, the adjustable screw and nut h' in the end of said bar, and the

spring h², attached to the frisket-bar i and adapted to release the friskets when said bar h is pressed outward, all substantially as and for the purposes hereinbefore set forth.

5. In a platen printing-machine, the combination of the connecting-rod G, with the truck g, adjustable in the slot in the end of said connecting-rod G and adapted to engage with the projection c³, all substantially as and for the purposes hereinbefore set forth.

6. In a platen printing-machine, the combination of the lever K, mounted at one end upon the shaft k and having at its other end the truck K', adjustable in the slot K², said truck K' adapted to engage with the cam M, the shaft k, having a flat surface k', the bridge k², the lever L, secured to said shaft k by means of the bridge or clip k², the spring l, one end of which bears against the projection l' and the bracket l², and said bracket l², all substantially as and for the purposes hereinbefore set forth.

7. In a platen printing-machine, the combination of the lever L, mounted upon the shaft k, the truck K', mounted in the end of the lever L' and adapted to engage with the cam g', and the cam g', adapted to engage with the truck K' and adjustable in the end of the connecting-rod G, all substantially as and for the purposes hereinbefore set forth.

8. In a platen printing-machine, the combination of the lever L, having a stop l⁴, the lifter-bar N', hinged to the lever L, the spring M², adapted to press upward against the bar M', the lever m', attached to the lifter-bar N' and carrying a truck m², the rod M³ and lever m⁴, hinged to said lifter-bar N', said lever m⁴ having a tail-piece, the truck M⁴ at the end of said lever m⁴, the fingers d⁵, carried by the hinged rod M³, the brackets d⁶, attached to the lifter-bar N', the lifters d⁸, hinged in said brackets, the spring d⁹, acting upon said lifters d⁸, all substantially as and for the purposes hereinbefore set forth.

In testimony that we claim the foregoing we have, this 3d day of July, 1888, set our hands and seals.

ALFRED MORFIT. [L. S.]
CHARLES BUTTERFIELD. [L. S.]
